United States Patent

Des. 239,445

Patented Apr. 6, 1976

239,445

HOLDER FOR LEDGER SHEETS OR THE LIKE

Allen L. Dixon, Portage, Mich., assignor to Master-Craft
Corporation, Kalamazoo, Mich.

Original design application Sept. 20, 1971, Ser. No.
182,299, now Patent No. 230,645. Divided and this
application Nov. 28, 1973, Ser. No. 419,676

Term of patent 14 years

Int. Cl. D19—03

U.S. Cl. D19—88

Fig. 5

Fig. 6

Fig. 7

FIG. 1 is a perspective view of a holder for ledger sheets or the like embodying my design, same being illustrated with the cover and clamping member in the closed position;

FIG. 2 is a perspective view similar to FIG. 1 and illustrating the cover and clamping member in the open position;

FIG. 3 is an enlarged scale left side elevational view of FIG. 1, an intermediate portion being broken away and omitted for convenience of illustration;

FIG. 4 is an enlarged scale fragmentary left side elevational view of FIG. 2;

FIG. 5 is a top plan view of FIG. 1;

FIG. 6 is a rear elevational view thereof; and

FIG. 7 is a bottom plan view.

This application is a division of copending application Ser. No. 182,299, filed Sept. 20, 1971, now Pat. No. D. 230,645.

I claim:

The ornamental design for a holder for ledger sheets or the like, as shown and described.
